UNITED STATES PATENT OFFICE.

CHARLES E. MILLER, OF CHICAGO, ILLINOIS, ASSIGNOR TO UNIVERSAL ARCH COMPANY, OF CHICAGO, ILLINOIS, A CORPORATION OF ILLINOIS.

LOCOMOTIVE-ARCH.

1,364,572.

Patented Jan. 4, 1921.

Application filed April 14, 1919. Serial No. 289,954.

To all whom it may concern:

Be it known that I, CHARLES E. MILLER, a citizen of the United States, and resident of Chicago, in the county of Cook and State of Illinois, have invented certain new and useful Improvements in Locomotive-Arches, of which the following is a specification.

My invention relates to locomotive arches and particularly to a novel arch brick.

10 One of the objects of my invention is to provide a brick construction which will eliminate the necessity for right and left hand bricks for a span, whether adapted to rest upon arch tubes or on studs. This is important from the standpoint of both the producer and the user as will readily be understood.

20 A further object is to provide in a brick of the character just described, a locking device which shall be positive and serve to hold the bricks against movement in all directions until worn or burnt to the minimum of safety.

25 A further important object is to provide a construction which in service will avoid a continuous straight line joint at the center of the arch or junction of the bricks which would provide a channel or runway for cinders when the engine is operating. The creation of such a channel results in rapid abrasion of the arch at that point and shortens its life. The desired result is secured by reason of the fact that in my construction the joint is zig zag or staggered, 35 the joint at no point being longer than half the width of a brick.

From a producer's standpoint my brick presents many advantages, not the least of which is the reduction of breakage loss in handling and shipping, this for the reason that there are no small or fragile tongues or projections from the ends of the bricks and no thin edges which might be chipped or broken. The projecting portions, if they 45 may thus be called, are massive and not readily broken.

Any novelty residing in a construction in which curved bricks are progressively thickened from the supported ends to the high point of the bricks is described and claimed in my co-pending application, Serial No. 363,463, filed March 5, 1920.

The invention will be more readily under-

stood by reference to the accompanying drawings, wherein:

Figure 1 is a transverse sectional view through a portion of a locomotive arch, the bricks composing the arch being formed in accordance with my invention;

Fig. 2 is a plan view of one of the bricks;

Fig. 3 is a similar view showing similar bricks adapted for employment in a longer span, a key-brick being employed;

Fig. 4 is a plan view of the key-brick;

Fig. 5 is a sectional view of a slightly modified arch brick construction and

Fig. 6 is a fragmentary plan view showing the zigzag form of the joint between adjacent bricks.

In the drawings it will be seen that the arch shown in Fig. 1 is supported on three arch tubes 10, the bricks composing the arch being curved and being slightly thicker at their meeting edges than at their point of engagement with the arch tubes. This provides for additional material at the point where the greatest wear or abrasion takes place, that is at the apex or high point of the arch; in other words the bricks are both curved and tapered.

The bricks 11, may be provided with one or more recesses 12 on their upper surfaces in order to lighten the same. The thinner end is provided with a socket or groove 13, adapted to fit the arch tube while the opposite end is shaped for interlocking engagement with a duplicate brick. The desired result is secured by so forming the interlocking ends of the bricks that each thereof shall have one-half of its end shaped to provide a transverse diagonal plane surface 14 extending entirely across the brick, the other half of the end being formed to provide a transverse diagonal plane surface 15, the planes of the two surfaces intersecting at a point 16 midway between the top and bottom of the brick, the surfaces 14, 15, forming approximately supplementary angles with the upper or lower surfaces of the co-operating bricks.

By reason of this arrangement the bricks are each provided with a relatively massive triangular projection at each side at the top and bottom of the brick, and each of these projections constitutes one-half of the width of the brick which eliminates right and left-hand bricks in forming

an arch, the advantages of which have heretofore been pointed out.

In the construction of Fig. 3 the bricks 17, 18, are identical with those heretofore described. However, as the span between the arch tubes 19 is greater than in the illustration of Fig. 1, I provide a key-brick 20 which may have parallel straight sides as shown, or may be curved; in any event the ends of the key-brick are identical with the ends of the arch bricks. This construction provides a self-supporting arch of considerably greater span than could otherwise be formed and the bricks comprising the span are securely interlocked against movement in any direction.

In the construction of Fig. 5 the arch bricks are substantially the same as those heretofore described except in that the plane surfaces 21, 22, do not extend entirely across the width of the brick; near the ends the surfaces 21, 22, are caused to extend substantially parallel to the transverse axis of the brick. The surfaces 23 are duplicated in both halves of the ends of the brick and all the advantages heretofore pointed out are present. There is the added advantage, however, that the edge formed by the junction of the outer surfaces and the surfaces 23 form a right angle whereas in the construction illustrated in the preceding figures an acute angle is formed. The advantage is that there is less likelihood of breakage where the angle is less acute.

The exact form of the brick ends need not be adhered to in order to secure advantageous results and modifications such as will readily occur to those skilled in the art and are considered to be within the spirit of my invention.

I claim:

1. In a locomotive arch, the combination of a plurality of duplicate bricks adapted to interlock at their ends and form a self-supporting arch, each brick having one-half of

the end which is adapted to coöperate with an adjacent brick provided with a transverse diagonal plane surface, the surface forming an acute angle with the upper surface of the brick, the other half of the said end being formed to provide a surface which forms an acute angle with the lower surface of the brick, the planes of the two surfaces intersecting at a point midway between the top and bottom of the brick, substantially as described.

2. In a locomotive arch, the combination of a plurality of bricks adapted to be interlocked in end to end relation, the ends of said bricks being shaped to provide relatively massive projections, each projection constituting one-half of the end of the bricks, the end surfaces of the two projections being oppositely diagonally disposed to form supplementary angles with the upper surface of the brick, the planes of the two diagonal surfaces intersecting at a point substantially midway between the top and bottom of the brick, substantially as described.

3. In a locomotive arch, the combination with supports, of a pair of upwardly and inwardly inclined bricks resting on said supports and adapted to be brought into abutting engagement at their upper ends, the abutting end of each brick being shaped to provide relatively massive projections, each projection constituting one-half of the end of the brick, the end surfaces of the two projections being oppositely diagonally disposed to form supplementary angles with the upper surface of the brick, the planes of the two diagonal surfaces intersecting at a point substantially midway between the top and bottom of the brick, substantially as described.

Signed at Chicago, this 11th day of April, 1919.

CHARLES E. MILLER.
